PHONOGRAPHIC APPARATUS

Charles Huenlich, Bloomfield, and Heinrich F. Max Gramann, Orange, N. J., assignors to Thomas A. Edison, Incorporated, West Orange, N. J., a corporation of New Jersey

Application January 5, 1932, Serial No. 584,770

7 Claims. (Cl. 274—17)

This invention relates to phonographic apparatus and more particularly, to phonographic apparatus adapted for use as a dictating machine.

It is an object of this invention to provide apparatus of the class described which is so constructed and arranged that the phonographic apparatus may be located at a distance from the dictator's position, while under the dictator's complete control.

10 It is a further object of this invention to provide improved apparatus of the class described which may be easily and quickly shifted from recording to reproducing position and vice versa.

It is still a further object of this invention to provide apparatus in which the shifting from recording to reproducing position may be carried out electrically and from a remote point if desired.

15 It is a further object of this invention to provide apparatus of the class described provided with back spacing or repeat mechanism which is so arranged as to be incapable of operation when the apparatus is in recording position.

It is a further object of this invention to provide apparatus of the class described in which the back space mechanism may be operated electrically from a remote point if desired.

20 It is still a further object of this invention to provide apparatus of the class described in which the back space mechanism is interlocked with the recording and reproducing mechanism in such manner that the back space mechanism cannot be operated when the apparatus is in recording position.

25 It is still a further object of this invention to provide apparatus of the class described which is so arranged that the feed screw mechanism cannot be disengaged when the apparatus is in either recording or reproducing position.

30 35 Still other objects and advantages of our invention will be apparent from the specification.

The features of novelty which we believe to be characteristic of our invention are set forth in the appended claims.

40 Our invention, itself, however, both as to its fundamental principles and as to its particular embodiments, may best be understood by reference to the specification and accompanying drawings, in which

45 Fig. 1 is a circuit diagram of a system according to our invention.

Fig. 2 is a diagrammatic view, partly in perspective, of mechanism and circuits in accordance with our invention.

50 55 Fig. 3 is a detailed elevational view showing one

form of the apparatus in reproducing position.

Fig. 4 is a similar view showing the apparatus in neutral position in readiness for a change of records.

In accordance with our invention we utilize a 5 dictating machine which may be of any of the well-known forms.

For the purpose of simplicity in explaining our invention, much of the mechanism of the dictating machine is not shown or described for the 10 reason that it forms per se no part of our invention, and is well known in the art. It will be understood that such a dictating machine as herein contemplated usually comprises a cylindrical record mounted upon a mandrel and arranged to be rotated at the desired speed by any 15 suitable source of power, such as an electric motor, although any type of driving motor may be employed for rotating the record.

The sound box and diaphragm construction 20 herein shown is the usual form of sound box and diaphragm construction used on dictating machines of a certain make, and since this is well known in the art, it is not described in detail. It will be understood, however, that other forms 25 of sound box and diaphragm mechanism than that referred to may be employed if desired.

The usual form of dictating machine employs a feed screw mechanism which serves to carry 30 the sound box and diaphragm mechanism along the record as the latter rotates, and since various forms of such feed screw mechanism are well known in the art, only so much of the feed screw mechanism has been illustrated as is necessary 35 to show the application of our invention thereto.

Referring to the drawings, reference character 1 designates a record mounted for rotation upon shaft 2. The sound box and diaphragm construction is indicated generically as 3 (Fig. 2) and carries a reproducing stylus 4 and a recording stylus 5. For the purpose of simplicity, we have shown the sound box 3 as being fed by an electric telephone 6 arranged to work into the sound box 3. The winding of the telephone 6 is supplied with current through a suitable 45 transformer 7 in series with a telephone receiver 11, and a second transformer 8, the primary of which includes in its circuit a suitable microphone 9 and source of current 10. The exact 50 circuit and mechanism employed for supplying currents to the telephone 6 forms per se no part of this invention and therefore is not described in detail.

It will be understood, however, that microphone 9 may be of any suitable type, and if de- 55

sired, an amplifier may be interposed between the microphone 9 and the telephone 6. For instance, the microphone 9 and receiver 11 may be of the so-called hand-set type and may be provided with a hook and switch contacts so that when the operator picks up the microphone 9 in preparation for dictation, the driving mechanism of the dictating machine is set into operation to cause rotation of the record. Such apparatus is described in the copending application of Louis A. de Berard and George T. Martin, Serial No. 467,854, filed July 14, 1930, entitled System of recording.

While we have shown the recording and reproducing mechanism as consisting of two separate and distinct parts, the telephone unit 6 of the sound box and diaphragm unit 3, it will be understood that any suitable mechanism may be employed for directly translating the electric currents in the telephone winding 6 into vibrations of a stylus, and conversely, in translating the stylus vibrations back into telephone currents. Such apparatus is shown, for example, in the Patent No. 1,762,175 to C. Huenlich, issued June 10, 1930, entitled Electrical sound recording and reproducing apparatus.

It will be understood that the apparatus shown and described in the said application and patent may be substituted for that herein shown without departing from the spirit and scope of our invention.

As already stated in the arrangement herein illustrated, the sound box 3 carries a diaphragm 40, pivoted at point 41 and also carries a floating weight 42 likewise pivoted at point 41. Mounted on the lower side of the diaphragm 40 is a stirrup or U-like member 45 at the lower point of which there is mounted the recording stylus 5. The reproducing stylus 4 is mounted on one end of a lever 43 pivoted at its intermediate point 44 on the floating weight 42, the opposite end of said lever lying within the stirrup or U-like member 45. As already stated, this construction is well known in the art.

In Fig. 2 the apparatus is shown in recording position in which the floating weight 42 and the diaphragm 40 are both permitted to drop freely to their lower extremities of travel, the floating weight 42 resting upon the record and being supported by an advance ball, not shown, which is mounted on the floating weight and which contacts with the record. The recording stylus 5 makes contact with the record while the reproducing stylus 4 is out of contact therewith.

As the record rotates, it will be understood that sounds supplied to the sound box vibrate the diaphragm 40 in the well known manner, and thereby engrave the record through the medium of recording stylus 5. In order to reproduce, the diaphragm 40 is lifted up by appropriate mechanism until the recording stylus 5 no longer contacts with the record. As the diaphragm 40 is lifted the base of the stirrup 45 contacts with the free end of the lever 43 and lifts up the floating weight 42, and forces the reproducing stylus 4 into contact with the record. The vibrations of the reproducing stylus are then transmitted through the lever 43 to the stirrup 45 and thence to the diaphragm 40 producing sound waves in the sound box.

In the arrangement shown, in recording, the diaphragm of telephone 6 is caused to vibrate by currents produced by the speaker's voice, and the vibrations of such diaphragm produce waves

which travel down into the sound box 3, impinging on the diaphragm 40 in the same manner as if the dictator had spoken directly into the sound box. Conversely, in reproducing, the sounds generated by vibration of the diaphragm 40 serve to set into vibration the diaphragm of the telephone 6 and the vibrations of the latter diaphragm cause a variation in the flux through the telephone windings and thereby cause the generation of currents.

Since all of the effects already explained are well known to those skilled in the art no further description is believed to be necessary for this part of the apparatus.

In order to provide for controlling the apparatus to shift from recording to reproducing position, and vice versa, at a distance, there is provided a cam 25, mounted for free rotation on shaft 26. The cam 25 has projecting therefrom an arm 27 which is in turn pivoted to one end of a link 28, the opposite end of which is pivoted to an arm 29 mounted for sliding movement upon a squared shaft 30, in such a manner that arm 29 may slide freely on shaft 30 but is caused to rotate therewith. The shaft 30 carries a commutator 59 which will hereafter be described and is connected to the oscillating armature 31, having a pair of arms 32 and 33. The arms 32 and 33 are arranged to be attracted by the reproducing and recording magnets 34 and 35, respectively, the apparatus being shown in recording position.

A pair of switches or push buttons 36 and 37 are provided, the push button 36 serving to energize the reproducing magnet 34 and the push button 37 serving to energize the recording magnet 35, through a suitable source of current, such as 38. If desired the switches or push buttons 36 and 37 may be provided in the form of interconnected switches so that only one may be closed at a time as indicated in Fig. 1. It will be understood that if the push button 36 is closed when the apparatus is in recording position, the magnet 34 will be energized, and will attract the armature arm 32 and cause counterclockwise rotation of the armature until the arm 32 is opposite the face of magnet 34. Conversely, if the push button 37 is closed and push button 36 open, magnet 35 will be energized and the apparatus will be returned to the position shown.

When the push button 36 closes the circuit through reproducing magnet 34, the shaft 30 is rotated counterclockwise thereby rotating arm 29, in the same direction and rotating cam 25 in clockwise direction. The cam is so arranged as to engage the diaphragm 40 and lift it upward, bringing the apparatus into reproducing position as shown in Fig. 3. Conversely, when recording switch 37 is closed the reverse operation takes place and the diaphragm 40 is lowered, carrying reproducing stylus 4 out of contact with the record and bringing recording stylus 5 into engagement with the record.

If an amplifier is used, it is desirable to provide means for energizing the various amplifier circuits whenever the telephone is removed from its stand, and also to provide means for interchanging the amplifier input and output circuits when changing from recording to reproducing position.

This may be accomplished by providing supplementary switch contacts 181 and 182. Switch contact 181 is secured to switch contact 36, and is movable therewith, by means of insulation 183, and switch contact 182 is similarly secured to switch contact 37, by means of insulation 184.

5 Switch contact 181 is connected to the input terminal 172 of amplifier 170, and switch contact 182 is connected to the amplifier output terminal 174. Switch contacts 186 and 187 are connected together and through the voice winding of the 10 recording and reproducing apparatus, diagrammatically indicated at 180, to amplifier output terminal 173, and to amplifier input terminal 171 and to ground. Switch contacts 185 and 188 are connected together, and through the dictator's telephone set to amplifier terminals 171 and 173 and ground.

15 Amplifier 170 is supplied with operating voltage by the power supply unit 175, which in turn draws its voltage from any suitable source 179 through the transformer 178. The operation of the power supply unit is controlled by relay contact 176, actuated by coil 177 which is in series in conductor 100, which carries the motor current.

20 It will be seen that when the apparatus is in recording position, the dictator's telephone is connected in the input circuit of the amplifier, while the recorder is connected in the output circuit of the amplifier, whereas when the apparatus is in reproducing position, these elements are interchanged.

25 In order to permit of back spacing or repeating small portions of the record during reproduction, a back space mechanism is provided which in the 30 present arrangement is attached to the feed screw mechanism. The feed screw mechanism comprises feed screw 15 which is caused to rotate whenever the record is in motion. In engagement with the feed screw 15 there is provided 35 a continuous wormwheel 16 mounted upon shaft 17 and fixed thereon. The shaft 17 passes through a suitable bracket 18 mounted for sliding engagement upon shaft 19, and as will be understood, the sound box assembly 3 is secured 40 in any suitable manner to the bracket 18 so as to be carried across the record by rotation of the shaft 15. The arrangement of feed screw mechanism and worm herein shown is that found in a well-known make of transcribing machine 45 and more particularly described in Patent No. 1,979,829, granted November 6, 1934 on an application of H. F. M. Gramann, and entitled Phonographs, to which reference may be had.

50 It will also be understood that cam 25 is mounted upon the assembly, driven by the feed screw, and moves with the carriage across the record. For the purpose of providing for back spacing the shaft 17 may be provided with a ratchet 50 adapted to be engaged by pawl 51 pivoted upon armature 52 which in turn is pivoted at 53 and biased to its upward position by spring 54. The back space magnet 55 when energized causes clockwise rotation of armature 52 and pawl 51 thereupon rotates the ratchet 50 clockwise, rotating shaft 17 slightly, and carrying the bracket 18 to the right, as shown in Fig. 2, thereby moving the carriage backward a few grooves upon the record. Ordinarily shaft 17 is held against rotation whereby rotation of the feed 65 screw 15 causes record traversing movement of the bracket 18 as will be understood.

60 In order to prevent the possibility of the back space magnet 55 being energized accidentally, or otherwise, during recording, which would cause 70 dictation to be recorded upon a used portion of the record, an interlock is provided. This may take any number of forms, either mechanical or electrical, or combinations of both, but for the sake of simplicity, we prefer to utilize commutator 75 59, carrying an insulating segment 60 upon which

there rides a spring contact 58. The back space magnet circuit comprises a suitable source of power, such as 51, a push button or switch 56 and is completed through spring contact 58 to commutator 59 and thence from the shaft 30, 5 or directly from the commutator, if desired, through back space magnet 55 to the source 51. The insulated segment 60 is so related in its position to the position of the armature 31 that the back space magnet circuit is interrupted by 10 the commutator 59 except when the armature 31 is in reproducing position, in which case the spring 58 rests upon a conducting portion of commutator 59. When, however, the apparatus is in recording position the spring 58 rests upon 15 the insulated segment of commutator 59 and the circuit is thus open at that point, thereby preventing actuation of the back space magnet even though the switch 56 be closed.

20 For the purpose of permitting change of records, it is desired to move the sound box assembly to one extremity of its travel and in order to do this, we prefer to disengage the feed screw mechanism.

25 However, it is undesirable to do this with the apparatus either in recording or reproducing position because of possible injury and it is undesirable to disengage the feed screw mechanism with the apparatus either in recording or reproducing position. Therefore, we provide means for 30 lifting both the recording and reproducing styli out of engagement with the record into neutral position and we provide mechanism for disengaging the feed screw. Both of these mechanisms are provided with an interlock which positively prevents disengaging the feed screw mechanism until the recording and reproducing styli have been lifted out of engagement with the record. One form of such mechanism may comprise cam 70, positioned adjacent cam 25 and 35 free for rotation on shaft 26. The cam 70 when rotated clockwise as seen in Fig. 2 engages the floating weight 42 and lifts it up out of contact with the record, as shown in Fig. 4. As the floating weight moves upward it likewise 40 engages the diaphragm 40 and carries the latter with it, thereby removing both the recording stylus 5 and the reproducing stylus 4 from the record.

45 For the purpose of disengaging the feed screw mechanism there is provided a lever 65 secured on shaft 66, which is mounted for rotation. A link 67 is secured to the end of arm 65 and its lower extremity is pivoted to arm 68 engaging bracket 18. The end of shaft 66 is placed in proximity to the lever 71 and carries secured thereto a plate 69 which is so related in size and position to arm 71 as to be engaged thereby and prevented from rotating except when the arm 71 is thrown to the position shown in Fig. 4.

50 Under such conditions the lever 65 may be depressed, rotating shaft 66 clockwise, lifting up link 67 which in turn rotates bracket 18 upon shaft 19 and lifts the worm 16 out of engagement with the feed screw 15, whereupon the carriage carrying the sound box and its associated mechanism may be slid freely across the record. When the record is replaced and levers 65 and 71 returned to initial position as shown in Fig. 2, 65 the lever 65 is then locked against rotation.

70 Referring now more particularly to the circuit diagram of Fig. 1, we have shown a wiring diagram of a complete system embodying apparatus of the class described and arranged to be 75

completely controlled by the dictator from a remote position.

The entire apparatus may be energized from line contacts 80 and 81. Additional contacts 82, 83, 84, 85, 86, 87, 88, 89, 90, 91, 92, 93 and 94 are provided. Contacts 80 and 86 are arranged to be connected together as are contacts 81, 82 and 87, and similarly contact 83 is connected to contact 94, contact 84 to contact 89 and contact 85 to contact 88. Contacts 90, 91, 92 and 93 are all connected together.

The arrangement and operation of the various circuits will best be understood by considering a typical series of operations carried on by the dictator. It will be understood that the telephone transmitter and receiver used by the dictator are installed at any convenient place and that the various switches utilized by the dictator for controlling the apparatus are placed in a position convenient to the dictator, as, for instance, on a panel board or box, or on the handle or base of the telephone. The phonograph apparatus itself may be placed in a convenient location not necessarily near the dictator. Assuming that power is supplied to the phonograph apparatus through line contacts 80 and 81 and that a fresh record is on the machine, the armature 31 will be in recording position because switch 37 will be closed or will have been previously closed.

While the exact form of this switch may be varied it may comprise an operating cam 130 spring biased to the position shown and may be provided with a passing contact such that switch 37 passes through closed position whenever the cam 130 returns to or is moved out of its normal recording position as shown.

Consequently, the apparatus is normally in position to record and is maintained out of recording position only when the dictator holds the operating cam 130 either in a position to reproduce or to repeat as will be described later.

Assuming that the dictator wishes to record a message he picks up the telephone "T" which may be the conventional form of separate transmitter and receiver or may be a hand set as shown diagrammatically. When the telephone is removed from its stand, switches 97 and 101 which have previously been held in open position are closed in any suitable manner, for example, by means of springs. Closure of switch 97 energizes the circuit of microphone 9. Simultaneously the motor 121 which supplies power for rotating the record is set into operation. The motor circuit is as follows: From contact 81, conductor 120, motor 121, conductor 123, contact 91, contact 90, conductor 103, switch contact 102, switch arm 101, conductor 100, contact 86 to line contact 80. The flow of current in conductor 100 energizes coil 177, closing relay 176 and supplying power to the power supply unit 175, which in turn energizes the amplifier 170.

Simultaneously, power is supplied from contact 81 through conductor 124, lamp 125 to switch 126, 65 which is closed by a record when the latter is in operative position upon the mandrel but is otherwise open, thence through switch 127, thence to conductor 103, contact 102, switch arm 101, conductor 100, contact 86, to line conductor 80. 70 Switch 127 is associated with the movable friction brake disc of a conventional motor speed governor so that it will be closed by such disc when the motor reaches speed but otherwise is open. Consequently, lamp 125 will be illuminated 75 when the telephone is removed from its stand, a

record is on the mandrel, and the motor is operating at speed. Should any of these conditions not obtain, the lamp 125 will be dark and the dictator will be warned that the apparatus is not in condition to record.

Also, power is supplied to lamp 137-A, thence through conductor 138, to commutator 139, thence through conductor 140, to conductor 103 and back to line contact 80. The commutator 139 may be mounted upon shaft 30 and is so arranged that 10 when armature 31 is in recording position commutator 139 completes the circuit between conductor 138 and conductor 140, energizing the recording lamp 137-A. If the armature 31 is in reproducing position commutator 139 opens the 15 circuit through lamp 137-A and closes the circuit through the reproducing light 137-B, conductor 141, commutator 139 and conductor 140.

Therefore, after picking up the telephone the dictator will wait until lamps 125 and 137-A 20 light, indicating that the apparatus is in readiness to record. He will also observe lamp 154 which is arranged to be lighted when the record is nearly completed, the circuit being as follows: conductor 124, lamp 154, conductor 155, switch arm 156, 25 switch contact 157, resistance 158, conductor 147 to conductor 103, thence through switch 101 to the other side of the line. If the lamp 154 is not lighted the dictator may begin his dictation. His first act will be to press the push button PB which 30 may be mounted upon the handle of the telephone. The push button separates contacts 106 and 107 and closes contact 106 against contact 108, thereby completing a circuit which causes operation of suitable clutch mechanism (not shown) 35 to connect the driving motor to the mandrel, causing rotation of the record. The circuit is as follows: contact 81 to contact 82, conductor 105 to contact 106, contact 108, conductor 110, contact 85, contact 88, conductor 111 through clutch magnet 114-A, contact 113, switch arm 112, conductor 115, contact 92, contact 90, conductor 103 and thence to line terminal 80. The energization of clutch magnet 114-A attracts armature and switch arm 112 moving it to the position shown 45 in dotted lines and simultaneously interrupting the circuit through clutch magnet 114-A and preparing the circuit through declutching magnet 114-B.

The clutch mechanism is not shown and the 50 details of the armature and contact arm 112 are not shown since both of these are well known in the art.

Reference may be had to the Langley Patent No. 1,380,486, dated June 7, 1921, for details of 55 the clutching mechanism.

The record is now rotating under the sound box and any material dictated will be recorded. If the dictator wishes now to hear what has been dictated he operates switch control 130 opening 60 switch 37 and closing switch 36 against the contact 36-A, whereby power is supplied through conductor 133, reproducing magnet 34 and conductor 132 to return conductor 103, moving armature 31 to reproducing position, thereby opening the circuit through recording lamp 137-A and closing the circuit through reproducing lamp 137-B, and interchanging the input and output circuits of the amplifier. Further operation of the switch control 130 closes contact 36-A 65 against contact 36-B, thereby supplying power to conductor 134 to contact 83 to contact 94, conductor 135, through back space magnet 55 through commutator 59, conductor 136 to contact 93 to contact 90 and return conductor 103, 70 75

whereupon the carriage will be back-spaced as previously described.

If the dictator now wishes to make a correction he releases switch control 130 whereupon contacts 36 and 36-A and 36-B are opened and the apparatus returns to recording position. The dictator now closes contact 143 against contact 151. Closure of these contacts supplies power to conductor 152 thence through correction relay 153, conductor 146, conductor 147 and return conductor 103, energizing the correction relay, attracting its armature which is provided with a pencil or other suitable apparatus for marking upon a slip or index provided for the purpose. Such apparatus per se is described in Patent No. 1,278,565, to E. B. Basch, issued September 10, 1918, to which reference may be had. After completing the correction the dictator continues.

At the termination of the first message, to indicate its completion, he closes switch contact 142 against contact 142', thereby supplying power to conductor 144 and energizing relay 145, attracting its armature and making a mark for the end of the message. Further operation of contact 142 closes contact 148 supplying power to conductor 149, energizing the "rush" magnet 150 and appropriately marking the record slip. The operating member for the length, rush, and correction switches is preferably arranged to be biased to neutral position so that normally none of these switches is closed. It may be in the form of a cam which when rotated in one direction causes closure of the correction switch and when rotated in the other direction from neutral position first causes closure of the length switch and on further rotation, closure of the rush switch.

The dictator may then continue with other messages as will be understood. As the carriage approaches the end of its travel on the record, switch contact 156 is brought into engagement with contact 157 thereby closing a circuit through finish lamp 154 as already described, warning the dictator that the record is nearly finished. Further travel of the carriage closes contact 157 against contact 159, thereby short-circuiting resistance 158 and causing lamp 154 to burn more brightly indicating that no more dictation can be recorded upon the record in use. The dictator then releases push button PB permitting contact 106 to separate from contact 108 and to close against contact 107, thereby supplying power to conductor 109, to contact 84, declutching magnet 114-B, through line 115 to contact 92, to contact 90, to return conductor 103, energizing the declutching magnet and returning switch arm and armature 112 to the position shown in full lines, thereby interrupting the circuit through declutching magnet 114-B and preparing the circuit through declutching magnet 114-A and declutching the mandrel from the driving motor.

The dictator then replaces the telephone upon its stand, opening switches 97 and 101, thereby de-energizing the microphone and driving motor and amplifier circuits respectively. The dictator may then wait a few moments to permit time for an attendant to replace the completed record with a fresh record and may then take up the telephone in preparation for continuing his dictation.

While we have shown herein only a single machine, it will be understood that two phonographs may be utilized provided with interconnecting circuits for continuous recording as described in the copending application of C. Huenlich, Serial No. 581,870, assigned to Thomas A. Edison, Incorporated, by means of which the necessity for

the dictator to hang up his receiver to permit of change of records is eliminated and continuous dictation over as long a period as may be desired is possible.

While we have shown and described certain preferred embodiments of our invention, it will be understood that modifications and changes may be made without departing from the spirit and scope of our invention as will be apparent to those skilled in the art.

We claim:

1. In a dictating machine, in combination, a record holder, sound recording and reproducing apparatus selectively shiftable to neutral, recording and reproducing positions with respect to a record on said holder, remotely actuatable control means operable to effect the shifting of said apparatus to either recording or reproducing position, a control device actuatable independently of said control means for shifting said apparatus to neutral position, feed mechanism for causing said apparatus to advance across said record upon rotation thereof, means for disengaging said apparatus from said feed mechanism, and means adapted to coact with said control device positively to prevent such disengagement when said apparatus is in recording or reproducing position.

2. In a dictating machine, in combination, a record holder, sound recording and reproducing apparatus selectively shiftable to neutral, recording and reproducing positions with respect to a record on said holder, remotely actuatable control means operable to effect the shifting of said apparatus to either recording or reproducing position, a control device actuatable independently of said control means for shifting said apparatus to neutral position, feed mechanism for advancing said apparatus across said record with rotation thereof, means for disengaging said apparatus from said feed mechanism and comprising an actuating lever, and means associated with said lever and adapted to coact with said control device positively to prevent actuation of said lever when said apparatus is in recording or reproducing position.

3. In a system of the character described having a record support and a movable speed governor element, a phonograph, a dictator's station comprising means for causing operation of said phonograph, an electrically operable signal, an energizing circuit for said signal, and a pair of normally open switches included in said circuit, one of said switches being associated with said record support so as to be closed by a record only when the latter is operatively positioned on such support, and the other of said switches being associated with such governor element and adapted to be closed by such element only when the latter reaches a position corresponding to suitable recording speed of the phonograph.

4. In a system of the character described, a phonograph having a rotatable record support and a speed responsive device, an energizing circuit for a part of said system, and a pair of normally open switches included in said circuit, one of said switches being associated with said record support so as to be closed by a record only when the latter is operatively positioned on said support, and the other of said switches being associated with said speed-responsive device to be closed by the latter when said phonograph is driven at not less than a predetermined speed.

5. In a system of the character described, a phonograph adapted to record and reproduce se-

- lectively and having a rotatable record support and a speed-responsive device, a dictator's station comprising means actuatable to cause the operation of said phonograph and the termination of operation thereof and means operable to cause the shifting of said phonograph from recording to reproducing position and vice versa, means for giving at said station distinctive indications respectively of the said positions of the 5 phonograph, an independent signal at said station, an energizing circuit for said signal and a pair of normally open switches included in said circuit, one of said switches being associated with said record support so as to be closed by a record only when the latter is operatively positioned on such support and the other of said switches being associated with said speed-responsive device and adapted to be closed thereby when the phonograph is operated at not less than a predetermined speed.
- 10 6. In a system of the character described, a phonograph adapted to record and reproduce selectively and having a rotatable record support and a speed-responsive device, a dictator's station comprising means actuatable to cause the operation of said phonograph and the termination of operation thereof and means operable to cause the shifting of said phonograph from recording to reproducing position and vice versa,

- 25

means for giving at said station an indication that the phonograph is in the recording position, an independent signal at said station, an energizing circuit for said signal and a pair of normally open switches included in said circuit, one of said switches being associated with said record support so as to be closed by a record only when the latter is operatively positioned on such support and the other of said switches being associated with said speed-responsive device and adapted to be closed thereby when the phonograph is operated at not less than a predetermined speed.

7. In a system of the character described, a phonograph having a record support and a sound box carriage arranged for relative traversing movement in respect of a record on such support, a dictator's station remote from said phonograph and comprising means for controlling the operation of said phonograph, electrically operable signaling means at said station, and a pair of normally open switch devices disposed in the path of such traversing movement of said carriage at points respectively corresponding to proximity to the end of the record and to the end of the record, each of such switch devices being in 20 25 circuit with said signaling means.

CHARLES HUENLICH.
HEINRICH F. MAX GRAMANN.

CERTIFICATE OF CORRECTION.

Patent No. 2,092,917.

September 14, 1937.

CHARLES HUENLICH, ET AL.

It is hereby certified that error appears in the printed specification of the above numbered patent requiring correction as follows: Page 5, second column, line 49, claim 3, strike out the comma and words ", a phonograph" and insert the same after "described" in line 47, same claim; and that the said Letters Patent should be read with this correction therein that the same may conform to the record of the case in the Patent Office.

Signed and sealed this 23rd day of November, A. D. 1937.
